UNITED STATES PATENT OFFICE.

PHILIP MINDUM AND LEON HEYNE, OF CHICAGO, ILLINOIS.

DESIGN FOR A SIDEBOARD.

42,842.

Specification for Design.

Patented July 30, 1912.

Application filed March 27, 1912. Serial No. 686,626. Term of patent 7 years.

To all whom it may concern:

Be it known that we, PHILIP MINDUM and LEON HEYNE, citizens of the United States, and residents of Chicago, in the county of Cook and State of Illinois, have invented a new, original, and ornamental Design for a Sideboard; and we do hereby declare that the following is a specification thereof, reference being had to the accompanying drawing, forming a part thereof, in which the figure is a perspective view of the design.

We claim:

The ornamental design for a side board, as shown.

PHILIP MINDUM.
LEON HEYNE.

Witnesses:

FRIEDA T. LEBERSTEIN,
MICHAEL J. STARK.
